BOBBIN FOR WEFT-REPLENISHING LOOMS

Application filed December 6, 1928. Serial No. 324,133.

This invention relates to a bobbin and the mass of yarn wound thereon such as may be employed in a weft replenishing loom and it is the general object of the invention to render an ordinary hard wound bobbin more suitable for cooperation with weft detectors.

The ordinary weft replenishing loom usually employs a feeler or weft detector which is brought in contact with the yarn of the active 10 shuttle at regularly recurring intervals during the operation of the loom. In the case of silk and similar fine yarns the tendency is to wind as much yarn on the bobbin as possible and this is accomplished by employing a relatively high tension during the winding operation. The result is the formation of a bobbin 15 the weft detector engaging surface of which is very hard, so hard in fact that certain types of detectors coat with the detector the same way that the bare barrel of the bobbin does, that is, to give indication of weft exhaustion. Under these conditions the indications are always premature and the weft replenishing mechanism is depleted of its 20 serve bobbins to no useful purpose.

In side slipping weft detectors for instance there is an element which tends to move to the side along the bobbin while in contact with the latter, being urged to undergo this movement either by a force derived from the bobbin itself or from some yielding force which is applied only after the detector engages the bobbin. The teeth on such a detector must be able to embed themselves an appreciable 25 amount in the yarn on the bobbin in order to prevent premature indication and it is an important object of my present invention to wind the bobbin so that those coils or convolutions of yarn which are to be engaged by 30 the detector will be wound under less tension and will therefore be more readily penetrated by the teeth of the detector than is the case with the remaining mass of yarn.

Winders usually have some form of tensioning device which engages the yarn as it passes from the supply to the bobbin being wound and this tension is ordinarily variable. In the case of one form of winder which has gone into very common use a pair of yieldable disks are provided between which the

yarn runs, said disks being held together by means of an adjustable weight which may cause a variation in the pressure existing between the two disks. My invention is not concerned with the particular mechanism for varying the pressure on the disks or the tension to which the yarn is subjected but is directed more particularly to the wound bobbin.

With these and other objects in view which will appear as the description proceeds, my invention resides in the combination and arrangement of parts hereinafter described and set forth in the claims.

In the accompanying drawings wherein a 65 convenient embodiment of my invention is set forth,

Fig. 1 is a top plan view of a bobbin made according to my present invention and showing the same in contact with the rear end 70 of a weft detector,

Fig. 2 is a vertical section on line 2—2 of Fig. 1 on an enlarged scale showing the difference in the character of coils of yarn.

Referring to Fig. 1 I have shown a bobbin 75 having a butt 10 and a smaller barrel portion 11. The butt may be provided with the usual rings 12 to hold the same in the springs of the shuttle not shown. A weft detector 13 is representative of any one of a number of 80 mechanisms of this type, there being shown herewith the rear portion of a detector arm of a side slip type, said arm having teeth 14 which are adapted to be embedded in the yarn of the bobbin. The unwound bobbin together with the detector of themselves form no part of my invention but may be of usual construction.

My invention relates more particularly to the yarn on the bobbin and in carrying my 90 invention into effect I divide the bobbin generally into two zones, one of which has the yarn thereon wound tightly and the other wound under less tension. As shown in the drawings I provide a zone 20 near the butt 95 of the bobbin and of sufficient length so that any of the usual types of weft detectors will be likely to engage yarn lying in this zone. The coils of this zone are wound loosely and under a comparatively low tension so that the 100

teeth 14 of the detector are easily embedded in the coils of the zone 20.

The remainder of the yarn is located in the zone designated at 30 and may be tightly wound in order to increase the carrying capacity of the bobbin. Inasmuch as the weft detector will ordinarily have no engagement whatever with the coils in the zone 30 the yarn comprising this portion of the bobbin 15 may be wound under as tight a tension as desired.

The bobbin will be transferred as is usual by well-known mechanism into any of the shuttles in common use and when so placed 20 will have the zone 20 presented to the detector 13. Because of the fact that this portion of the bobbin is soft it will coact properly with the detector to prevent premature indication.

25 From the foregoing it will be seen that I have provided a very simple means for rendering a bobbin particularly usable with weft detectors, a portion of the bobbin being wound sufficiently soft to cooperate properly with the detector and the remainder of the bobbin being wound under increased tension so as to increase the carrying capacity of the bobbin. A single continuous strand of yarn 30 is wound under varying conditions of tension and thereby produces a bobbin especially adaptable for weft replenishing looms.

Having thus described my invention it will be apparent that changes and modifications may be made therein by those skilled in the art without departing from the spirit and scope of the invention and I do not wish to be limited to the details herein disclosed, but what I claim is:

1. A bobbin for weft replenishing looms 40 having yarn wound thereon a portion of which is tightly wound and another portion of which is loosely wound.

2. A bobbin to cooperate with a weft detector having yarn wound thereon in two zones, the yarn in the zone to cooperate with the detector being loosely wound and the 45 yarn in the other zone being tightly wound.

3. A bobbin to be used with a weft detector dependent upon its ability to penetrate the 50 yarn to prevent indication of weft exhaustion, said bobbin having a mass of loosely wound yarn positioned to cooperate with the detector and having another portion of tightly wound yarn out of operative position with respect to the detector.

4. A bobbin for use with a weft detector, 55 said bobbin being wound with a continuous piece of yarn a portion of which is wound loosely and the remainder of which is wound tightly.

5. A bobbin for cooperation with a weft detector having a relatively soft mass of yarn positioned to cooperate with the detector and having the remainder of the mass of yarn 60 relatively hard.

6. A bobbin to be used with a weft detector having yarn wound thereon a portion of which is under relatively low tension to cooperate with the detector and the remainder of which is under relatively high tension to increase the carrying capacity of the bobbin. 70

In testimony whereof I have hereto affixed my signature.

RICHARD G. TURNER.
